UNITED STATES PATENT OFFICE.

CARL HORIX, OF CHICAGO, ILLINOIS, ASSIGNOR TO CARRIE C. HORIX, OF ST. LOUIS, MISSOURI.

BOTTLE-STOPPER REMOVER.

Application filed May 5, 1926. Serial No. 106,800.

This invention relates to a device for removing corks and crown cork stoppers from bottles, and has for its object the provision of a device of the class named which shall 5 be convenient and efficient in operation, attractive in appearance, economical to manufacture, and suitable for carrying in the pocket. Other objects will appear from the following description.

10 The invention is exemplified in the combination and arrangement of parts shown in the accompanying drawing and described in the following specification, and it is more particularly pointed out in the appended 15 claims.

In the drawings—

Fig. 1 is a vertical sectional view of one embodiment of the present invention showing the manner of applying the device to a 20 bottle stopper;

Fig. 2 is a side elevation of the device closed;

Fig. 3 is a section on line 3—3 of Fig. 1; Fig. 4 is a section on line 4—4 of Fig. 3; 25 Fig. 5 is a section on line 5—5 of Fig. 1; Fig. 6 is a central sectional view of the cork remover showing the manner of applying the remover to a crown cork;

Fig. 7 is a fragmentary view showing the 30 manner of applying the remover to a cork of small size.

In the embodiment of the invention shown in the drawing, a metal plate 10, shaped as shown in Fig. 1, has its narrower end bent 35 at right angles to the plane of the plate and folded upon itself to form a block 11. A cover 12 which may be of thinner material is hinged at 13 to the block 11 and provided with a flange 14, the edge of which bears 40 against the face of the plate 10 adjacent the edge of the plate so that the cover 12, plate 10 and flange 14, when folded together, form a closed case. A lug 15 may be provided on the flange 14 to engage the edge of the plate 45

10 to hold the device closed. The block 11 is provided with openings 16 inclined inwardly and downwardly and pins 17 are slidably mounted in the openings 16. The pins 17 are pointed at their lower ends and 50 provided with heads 18 which may be in the form of discs secured at the upper ends of the pins or may be formed by spirally winding a portion of the end of the pin upon itself in a plane at right angles to the axis 55 of the pin, as shown in Figs. 1 and 4 of the

drawing. When the pins are in retracted position, as shown in Figs. 1 and 3, their pointed ends will be disposed in the openings 16 which thus form guards for the ends of the pins. Lugs 19 are stamped inwardly on 60 the cover plate 12 in position to underlie the heads 18 when the cover is closed, thus retaining the pins in their retracted position. When the cover is opened, the lugs 19 will be withdrawn and the pins may be readily 65 projected thru the openings 16 into the position shown in broken lines in Fig. 1. When it is desired to remove a cork from a bottle, the device is placed in the position shown in Fig. 1 upon the top of the cork and the cover 70 12 is opened to permit the pins 17 to be projected into the cork as shown in broken lines in Fig. 1. This will give a firm hold upon the cork. It is not always essential that the pins be pressed into the cork for their full length, 75 and the pins, of course, may be made of varying lengths. In the embodiment illustrated in the drawings, the pins are shown as being of sufficient length to cross each other when fully projected and to permit them to pass 80 into overlapping position, the openings 16 are slightly staggered, as shown in Fig. 5 of the drawing. The openings may be arranged in a common plane if desired, and the pins made shorter so that they will meet or 85 approach each other when projected. After the pins have entered the cork, the cover 12 may be closed, a firm hold taken on the closed case and the whole device twisted slowly, preferably to the right or clockwise. This 90 will loosen the cork and by continuing the twisting motion while at the same time exerting a slight upward pull the cork will be easily removed. It will be seen that the case is of such shape that a firm grip may be 95 had upon it, and the position of the pins in the cork securely holds the cork so that the tightest stopper may be readily and quickly removed.

If the device is used in connection with a 100 small cork, as shown in Fig. 7, the pins will be projected a sufficient amount so that their pointed ends will be spaced from each other a distance commensurate with the size of the cork. The device is then applied to 105 the cork, as shown in full lines in Fig. 7, and the pins are projected into the position shown in broken lines. The cork may then be readily removed in the manner previously described.

Abutment lugs 20 are preferably formed on the plate 10 to limit the inward movement of the pins 17 so that when the pins are retracted and the cover closed, the pins 5 will be held against movement in either direction. It may sometimes be desirable to provide grooves 21 in the face of the plate 10 for engaging the peripheries of the heads 18 to assist in guiding the pins as they 10 are moved longitudinally. Although these grooves may be advantageous in some cases, they are not always essential for the reason that the openings 16 are of sufficient 15 length to serve as guides for the pins in most conditions.

The plate 10 is provided, near its wider end, with an opening 22 and the inner edge of the opening may be slightly beveled, as shown at 23 in Fig. 6. This opening enables 20 the plate 10 to be used for removing crown corks in the manner illustrated in Fig. 6. The opening 22 is of such size and shape that when the edge 23 is inserted beneath the edge of the crown cork, the bar 24 at the 25 opposite side of the opening will rest upon the upper surface of the cork and form a fulcrum which enables the cork to be readily removed from the bottle by lifting on the downwardly and outwardly projecting 30 end of the closed case.

I claim:

1. A cork puller comprising a casing having guide openings at one side thereof, pins mounted in said casing and arranged to be 35 projected point first therefrom through said openings, and displaceable lugs for holding said pins in retracted position within said casing.

2. A cork puller comprising a case having pins mounted therein in position to be 40 projected point first through the wall of said case, and a closure for said case having one side thereof hinged to permit said case to be opened.

3. A cork puller comprising a case having a hinged side, pins disposed in said case in 45 position to be projected point first therefrom and means on said hinged side for retaining said pins in retracted position within said case when said side is closed.

4. A cork puller comprising a plate having a portion thereof folded upon itself to form a guide block, a cover member hinged to said guide block and forming with said 55 plate a housing, pins mounted within said housing and slidably mounted in openings in said guide block, stops for limiting the in-

ward sliding movement of said pins, and stops on said cover member arranged to engage said pins when said pins are retracted to their innermost position and said cover member is closed, for holding said pins in retracted position.

5. A bottle opener comprising a casing having pins therein for engaging a bottle stopper, and having an opening therein for engaging a crown cork.

6. A bottle opener comprising a plate having a guide block at one edge thereof, pins arranged to slide through openings in said guide block into engagement with a bottle stopper, said plate having an opening therethrough for receiving a portion of a crown cork to bring one edge of said opening beneath the edge of said crown cork in 75 position to lift said crown cork from a bottle.

7. A bottle opener comprising a casing having spaced side members, two edges of said casing being substantially parallel while the opposite edges are disposed at an angle to each other, and pins arranged to be projected at an angle to each other from the shorter of the parallel side edges of said case.

8. A bottle opener comprising a case having spaced side walls hinged together, stopper engaging pins disposed within said case and arranged to be projected therefrom through one edge of said case, means arranged to engage said pins when said case is closed to hold said pins in retracted position but permitting said pins to be projected when said case is opened, and a catch for holding said case in closed position.

9. A combined stopper extractor and crown cork remover adapted to be carried as a pocket article upon the person comprising a casing having parallel side walls, one of said side walls being hinged to open the 100 casing, pins mounted within the casing and movable from an initial inclosed position therein into a projected position for engaging a bottle stopper, means on said hinged walls of the casing for holding said pins in 105 retracted position within the casing, and means on the side of the casing for engaging a crown cork substantially as and for the purpose described.

In testimony whereof I have signed my 110 name to this specification on this 3rd day of May A. D. 1926.

CARL HORIX.
